CLAIM

The ornamental design for a shoe, as shown and described.

DESCRIPTION

The patent or application file contains at least one photograph executed in color. Copies of this patent with color photograph(s) will be provided by the Office upon request and payment of the necessary fee.

FIG. 1 is a front lateral perspective view of a shoe.

FIG. 2 is a lateral side view of the shoe of FIG. 1.

FIG. 3 is a medial side view of the shoe of FIG. 1.

FIG. 4 is a front view of the shoe of FIG. 1.

FIG. 5 is a rear view of the shoe of FIG. 1.

FIG. 6 is a top view of the shoe of FIG. 1.

FIG. 7 is a partially enlarged view of the shoe of FIG. 2; and, FIG. 8 is a partial detail view of the shoe of FIG. 2.

The broken lines show unclaimed subject matter only and form no part of the claimed design. The dash-dot rectangle enclosing a portion of the claimed area of FIG. 2 is included to indicate a partially enlarged view of a portion of the claimed area and forms no part of the claimed design. The areas within the color photograph surrounded by broken lines and partially obscured with translucent shading form no part of the claimed design.
